UNITED STATES PATENT OFFICE

SEHEIN MOHAMED BULMENI, OF BUENOS AIRES, ARGENTINA

LOCK

Application filed February 2, 1926. Serial No. 85,558.

The present invention relates to locks and more particularly to a lock having a special type of key for opening the lock. One of the objects of the invention is to produce a lock which will be burglar-proof and at the same time of cheap construction.

Another object of the invention is to provide a special type of key for opening the lock.

10 The invention will be understood from the following description taken in connection with the accompanying drawings, in which:

Fig. 1 is an elevation of the lock mechanism in one position with a portion of the lock 15 casing removed.

Fig. 2 is a view similar to Fig. 1, the mechanism being in another position.

Fig. 3 is a diagrammatic illustration of indicating mechanism used in conjunction with 20 the lock.

Figs. 4 and 5 are true views of the special key used in connection with the lock.

Referring to the drawings, the lock mechanism is enclosed in a casing 1 which may be 25 secured to a door, window, box, or any desired closure, apertures 2 being provided to secure the casing in its position by means of screws, rivets or the like. Secured to the casing is a pin 3 serving as a guide for a lock bolt 5 which is provided with a longitudinal slot 4 through which the pin 3 passes. To further secure the bolt 5 to the pin 3 a washer 6 and nut 7 are provided.

The outer end of the bolt 5 has a hook-like 35 projection 8 as shown in the drawing. On one side of the bolt 5 are cut a number of teeth 9 forming a rack thereon. Disposed to this side of the bolt and mounted on a pin 10 is a toothed segment 11 which engages a pinion 13, which in turn engages the rack 9. The 40 segment 11 has a segmental portion of smaller diameter than that of the toothed portion on which are provided projections 12. The pinion 13 is mounted on a pin 14 supported by a bridge 15 secured to the casing by means of 45 the nuts 16.

Links 17 and 18, secured to the bolt 5 by means of a pin 19, connect the bolt to levers 33 and 34 which are mounted in the casing by 50 means of pins 35 and 36 and secured to the

latter by means of washers 40 and 41 and nuts 37 and 38. At the lower end of the bolt 5 a pin 20 connects the bolt 5 to another lever 21, the pin sliding in a longitudinal slot 22 in the lever 21. At the opposite end of the lever 21 is provided another slot 23 in which a pin 24 secured to the bolt 25 makes a sliding connection between the lever 21 and bolt 25. The lever 21 is bowed and is mounted intermediate its ends on a bridge member 28, also bowed, 60 by means of a pin 26 and nut 27. The bridge member 28 is secured to the casing by means of the pins 29 and the nuts 30. Pins 31 and 32 connect the links 17 and 18 to the levers 33 and 34. The opposite ends of the levers 33 65 and 34 are connected to supplemental sliding bolts 41 and 42 by means of pins 43 and 44. These latter pins slide in segmental slots 45 and 48, while the pins 31 and 32 are guided in segmental slots 46 and 47. The bolt 25 is 70 guided by a longitudinal slot 49 and a guide member 50. Each of the supplemental bolts 41, 42 and 25 is provided with an aperture to provide connection with locking bars to lock the closure member on four sides, these apertures being indicated at 51, 52 and 53.

Concentric with and having a diameter slightly larger than the smooth portion of the segment 11, are slots 54 into which a portion of the special key referred to above is inserted. Secured to the casing on a pin 56 is a locking device 55 provided with a pawl for engaging notches 57 and 58 of the bolt 5. The locking device 55 has a bent portion 59 in proximity to the hollow pin 10.

Further supplemental locking means are provided by means of a bolt 93 disposed parallel to the bolt 5, said bolt 93 being mounted on an angle piece 85, 86. The bolt 93 has a reduced portion 87 surrounded by a 90 spring 89 bearing against the flange 86 of the angle piece 85. A pin 89 connects the bolt 93 with a manually operated lever 92 pivoted to the exterior of the casing at 91.

The key member illustrated in Figs. 4 and 5 comprises a hollow shank portion 60 having a wing 61 at one end thereof and an angular portion 64 at the other end. Integral with the wing 61 is a squared projection 62. Within the hollow shank is a slidably pin 63 100

adapted to be pressed against a lever 67 pivoted to the portion 64. At the other end of the lever 67 is pivoted a sliding pin 68 mounted in the portion 64. The projection 65 at the end of the key guides the key in its turning movement in the lock. In the modified form of key shown in Fig. 5 the lever mechanism may be substituted by a plain key 71.

10 If desired the lock may be provided with indicating devices for indicating calendar dates, etc., as shown in Fig. 3. A series of notched wheels 75, 79, 81, 82, 83 and 84 bear various indices for this purpose. These 15 wheels are mounted on pins 72 secured to the casing by means of bridge members 73, 76 and screws 74 and 77. The wheels referred to above are held in position by the pawls 97 which are held in engagement with the wheels by a spring 96 surrounding the pin 95 guided in supports 94.

The means for releasing the pawls consists of a bar 99 having extensions 100 and 102 thereon. A disk 105 having a projection 109 25 may be rotated by means of the key 60. This disk is provided with abutments 106, 107 adapted to bear against the bolt 104. A second projection 110 is adapted to trip the lever 112 which presses against the bar 99 30 pivoted at 98 to press against the various pawl devices and release the indicating wheels.

To operate the lock mechanism the key 60 is inserted in the hollow pin 10, the projection 35 65 through its engagement with the end 59 of the member 55 releasing the locking device 55 from the notches 57 or 58 the pawl on the member 55 swings out of line with the notches as the notches are wider than the thickness of the pawl. The pin 68 further 40 engages the projections 12 to rotate the segment 11, thus reciprocating the bolt 5 through the pin 13. The bolt 5, through the medium of the links 17 and 18 and levers 21, 33 and 45 34, operate the supplemental bolts 25, 41, and 42. The bolt 93 is released by moving the lever 92 in the proper direction by some manual means connected to said lever.

Having thus described my invention what 50 I claim is:

A lock of the class described comprising in combination a casing, a bolt slidably mounted in said casing, said bolt being provided on one of its edges with teeth and a 55 pair of spaced notches on its opposite edge, a toothed segment pivotally secured to said casing, said segment being adapted to reciprocate said bolt, means for engaging said notches selectively to hold said bolt in its locked or open position, and a key operating means for simultaneously rotating said segment and releasing said holding means.

In testimony whereof I affix my signature.
